UNITED STATES PATENT OFFICE.

MARGARET E. MORRIS, OF ST. LOUIS, MISSOURI, ASSIGNOR OF SIX-SEVENTHS TO CHARLES I. MORRIS, FRANCIS E. MORRIS, W. J. MORRIS, R. M. MORRIS, CHARLES J. KENNEDY, AND CLEMENS RUEMMLER, OF ST. LOUIS, MISSOURI.

MACHINE FOR PACKING SHOE-UPPERS.

SPECIFICATION forming part of Letters Patent No. 715,210, dated December 2, 1902.

Application filed April 1, 1902. Serial No. 100,994. (No model.)

To all whom it may concern:

Be it known that I, MARGARET E. MORRIS, of the city of St. Louis, State of Missouri, have invented certain new and useful Improvements in Machines for Packing Shoe-Uppers, of which the following is a full, clear, and exact description, reference being had to the accompanying drawings, forming a part hereof.

My invention relates to machines for packing shoe-uppers; and it consists of the novel construction, combination, and arrangement of parts hereinafter shown, described, and claimed.

My object is to construct a machine for packing shoe-uppers and the like; and my invention consists of a suitable table, a bundle-forming box upon the table and open at the front and top and having vertical slots extending downwardly through the upper edges of its sides, a packer-plate adapted to operate up and down in said box, arms extending laterally from said plate through said slots and downwardly outside of said box, guides for said arms, a foot-lever under the table, a yoke connecting the lower ends of said arms to said foot-lever, said yoke and said arms operating through the table, a weight or its equivalent arranged to hold said foot-lever normally elevated, thus holding the packer-plate normally above said box with said arms out of said slots, so that said packer-plate may be tipped backwardly out of the operator's way, and stops to limit the backward motion of said plate.

Figure 1 is a side elevation of a machine for packing shoe-uppers arranged for use, the table being shown in section and parts being broken away to economize space. Fig. 2 is a top plan view of the parts shown in Fig. 1. Fig. 3 is a vertical central section on the line 3 3 of Fig. 2, the parts below the table being omitted.

Referring to the drawings in detail, the bundle-forming box comprises the base-plate 4, secured rigidly upon the table 5, the sides 6 and 7 extending upwardly from the base 4 and having the vertical slots 8 and 9 extending downwardly from their upper edges, and

the back 10 connecting the rear edges of the sides 6 and 7. The box thus produced is open at the front and at the top. The packer-plate 11 is adapted to fit within the box and move easily up and down. The bar 12 is secured to the packer-plate 11 and extends laterally beyond the side edges of said plate, thus producing the arms 13 and 14, which extend outwardly through the slots 8 and 9 and then downwardly outside of the side pieces 6 and 7. The blocks 15 and 16 are secured to the outer faces of the side pieces 6 and 7 in front of the slots 8 and 9, and the guide-plates 17 and 18 are secured to said blocks 15 and 16 and extend backwardly outside of the arms 13 and 14.

The yoke comprises the arms 19 and 20, 65 pivotally connected to the lower ends of the arms 13 and 14 and extending downwardly and then inwardly and secured to the connecting-rod 21, said connecting-rod extending downwardly to the foot-lever. The brace 22 70 is inserted between the central portions of the arms 19 and 20 and has a central opening 23. The upper end of the connecting-rod 21 has an opening 24. The foot-lever 25 is pivotally attached to the floor, and the 75 lower end of the connecting-rod 21 is pivotally attached to the foot-lever. A U-shaped loop 26 is attached to the floor and extends over the foot-lever to limit its upward motion and has teeth 27 to engage the tongue 80 28, carried by the foot-lever, for the purpose of locking the foot-lever against upward motion. A rope 29 is attached to the upper end of the connecting-rod 21 through the 85 opening 24, extends upwardly through the opening 23, then over the pulley 30, attached to the lower face 31 of the table, then backwardly over the pulley 32, attached to the lower face of the table, and then downwardly, and the weight 33 is connected to the lower 90 rear end of said rope, the power of said weight being exerted to hold the foot-lever 25 normally elevated, thus holding the packer-plate 11 elevated above the upper end of the box, with the arms 13 and 14 out of the slots 8 and 95 9, as required to allow the packer-plate to tip

backwardly, as indicated by dotted lines in Fig. 1.

The stops 34 and 35 are attached to the plates 17 and 18 and extend backwardly and inwardly and are attached to the back of the box, as required to limit the backward motion of the arms 13 and 14.

The operator stands in front of the table and places the "uppers" or other similar material to be packed upon the plate 4 within the packing-box, and as frequently as desired the foot-lever 25 is operated to press the packing-plate 11 downwardly upon the bundle, and the foot-lever may be operated with a jerky motion, as required to pound the bundle to any desired extent. If desired, strings or other suitable ties may be inserted through the opening 36 in the back 10 and placed upon the plate 4 and the bundle packed upon the ties or strings, and then the ends of the strings may be united over the bundle, as required to hold it together.

I claim—

1. A device of the class described, comprising a suitable table; a bundle-forming box upon the table and open at the front and top, and having vertical slots extending downwardly from the upper edges of its sides; a packer-plate adapted to operate up and down in said box; arms extending outwardly from said plate through said slots and downwardly outside of said box; guides for said arms; a foot-lever under the table; a yoke pivotally connecting the lower ends of said arms to said foot-lever; a weight arranged to hold said foot-lever normally elevated, thus holding

the packer-plate normally above the upper end of said box with said arms out of said slots, so that said plate may be tipped backwardly out of the operator's way; and stops to limit the backward motion of said plate; substantially as specified.

2. In a device of the class described, a bundle-forming box; a packer-plate adapted to operate up and down in said box; arms extending outwardly from said packer-plate through the sides of said box; a foot-lever; a pivotal connection between the foot-lever and said arms; and means of holding the said foot-lever normally elevated so as to hold said packer-plate normally above the box so that it may be tipped backwardly out of the operator's way; substantially as specified.

3. In a device of the class described, a bundle-forming box; a packer-plate adapted to operate up and down in said box; arms extending outwardly from said packer-plate through the sides of said box; a foot-lever; a pivotal connection between the foot-lever and said arms; means of holding the said foot-lever normally elevated so as to hold said packer-plate normally above the box so that it may be tipped backwardly out of the operator's way; and stops to limit the backward motion of said plate; substantially as specified.

In testimony whereof I affix my signature in presence of two witnesses.

MARGARET E. MORRIS.
